(57) **CLAIM**

The ornamental design for a absorbent padding for absorbing body fluid excretions, as shown and described.

DESCRIPTION

FIG. 1 is a front elevational view of an absorbent padding for absorbing body fluid excretions showing my new design;

FIG. 2 is a enlarged front elevational view;

FIG. 3 is a side elevational view thereof;

FIG. 4 is a bottom plan thereof; and,

FIG. 5 is a top plan view thereof.

The indicia or broken lines shown on the figures are for illustrative purposes only and are hereby disclaimed as forming no part of Applicant's claimed invention.
